Primary Examiner — T Chase Nelson*Assistant Examiner* — Jonathan J. Han(74) Attorney, Agent, or Firm — Banner & Witcoff, Ltd.(57) CLAIM

The ornamental design for a shoe, as shown and described.

DESCRIPTION

FIG. 1 is a rear bottom perspective view of a shoe showing my new design;

FIG. 2 is a bottom view thereof; and,

FIG. 3 is a front bottom perspective view thereof.

The broken lines immediately adjacent to the ends of the shaded areas define the bounds of the claimed design and form no part thereof. The broken line circle and the unshaded area therein form no part of the claimed design. The broken lines depicting the remainder of the shoe form no part of the claimed design.
